UNITED STATES PATENT OFFICE

2,297,834

SPRING MOTOR

John Kalua Kahookano, La Salle, Ill.

Application March 20, 1941, Serial No. 384,398

4 Claims. (Cl. 185—39)

This invention relates to a novel construction of spring motor for rotating a driving shaft through a novel gear arrangement.

More particularly, it is an aim of the invention to provide a spring motor constructed and arranged whereby the power exerted by the spring may be employed for partially rewinding the spring.

Still a further aim of the invention is to provide a spring motor including a crown gear of large diameter, driven by a spring and enmeshed with a pinion of small diameter, keyed to the driving shaft for driving said driving shaft at an increased ratio relatively to the speed of rotation of the crown gear.

Still another aim of the invention is to provide novel clutch means, associated with the driving shaft for engaging it with or disengaging it from a rewinding shaft of the spring motor.

Other objects and advantages of the invention will hereinafter become more fully apparent from the following description of the drawings, which illustrate a preferred embodiment thereof, and wherein:

Figure 1 is a top plan view of the spring motor,

Figure 2 is a side elevational view of the same,

Figure 3 is a horizontal sectional view, on an enlarged scale, taken substantially along the plane of the line 3—3 of Figure 2,

Figure 4 is an enlarged vertical sectional view taken substantially along the plane of the line 4—4 of Figure 1,

Figure 5 is an enlarged horizontal sectional view taken substantially along the plane of the line 5—5 of Figure 2,

Figure 6 is an enlarged vertical sectional view taken substantially along the plane of the line 6—6 of Figure 1, and

Figure 7 is a vertical sectional view taken substantially along the plane of the line 7—7 of Figure 6.

Referring more particularly to the drawings, wherein like reference characters designate like or corresponding parts throughout the different views, 10 designates generally a housing of a spring motor including a lower section 11 and an upper section 12. The sections 11 and 12 are provided with abutting flanges 13 for receiving fastenings 14 for detachably connecting the sections. The housing 10, as best seen in Figures 3 and 5, is provided with a substantially cylindrical hollow interior 15. As seen in Figure 4, the bottom of the housing 10 is provided with a centrally disposed raised portion 16 having an upwardly opening recess 17 forming a journal or

bearing for the lower end of a shaft 18 which projects upwardly therefrom to a point below the level of the upper portion of the lower section 11.

A spring drum 19 is turnably mounted on the shaft 18 and is supported by the portion 16 which forms a bearing for the drum 19. A spiral spring 20 is disposed in the drum 19 and is fastened at its inner end in any suitable manner to the shaft 18, and at its outer end, in any suitable manner, to the inner side of the periphery of the drum 19. As best seen in Figure 3, the spring 20 is coiled in a counterclockwise direction from its inner to its outer end.

A crown gear 21 is disposed in the lower portion of the housing 10 and is keyed to the drum 19 and is supported by an annular anti-friction ball bearing means 22, as best seen in Figure 4, which rests on the bottom of the housing 10 and which permits the crown gear 21 to revolve freely within the housing.

A driving shaft 23 extends horizontally through the housing 10 and is journaled in anti-friction bearings 24 which are mounted in the flanges 13 and in diametrically opposed relationship to one another. A beveled pinion 25 is keyed to the shaft 23, within the housing 10, and meshes with the beveled teeth 26 of the crown gear 21.

A second shaft 27 extends horizontally through the housing 10 and is journaled in anti-friction bearings 28 which are disposed in the flanges 13. The shafts 23 and 27 are disposed at substantially the same level and are substantially parallel and are arranged above the level of the uppermost portion of the crown gear 21 and the shaft 18. A worm 29 is keyed to the shaft 27 and is disposed in the housing 10 to mesh with a worm wheel 30 which is keyed to the upper end of the shaft 18 and which is disposed above the drum 19.

The shaft 27 is provided with a ratchet wheel 31, which is keyed thereto, exteriorly of the housing 10. The housing 10 is provided with an extension 32 on which is pivotally mounted a dog 33, the free end of which is urged by a spring 34 into engagement with the teeth of the ratchet wheel 31, which teeth are arranged so that the shaft 27 can turn in a clockwise direction, as indicated by the arrow 35, in Figure 5, and the dog will retract the spring 34 to permit the free end of the dog to ride over the teeth. However, the dog 33 will engage the teeth of the ratchet wheel 31 to prevent the shaft 27 from being turned in the opposite or a counterclockwise direction, for a purpose which will hereinafter become apparent.

As best seen in Figures 1 and 2, the housing section 12 is provided with a raised portion 36

through which the shafts 27 and 23 extend and on the upper side of which is mounted a guide-way 37 having upwardly projecting bearing members 38 in which is journaled a pin 39 to which is connected a lever 40. Lever 40, at its pivoted end, is provided with a gear segment 41 the teeth of which mesh with the teeth of a rack bar 42, which is slidably mounted in the guide 37, as best seen in Figure 6 and Figure 7. The raised portion 35 is provided with a slot 43, disposed beneath the rack bar 42 and through which depends an arm 44 which is secured to the rack bar 42 and which is provided with a forked lower end 45. The arm 44 is adapted to slide in the slot 43 when the rack bar 42 is moved 10 relatively to the guide 37 by a swinging movement of the lever 40.

A gear 46 is slidably keyed to the shaft 23 by means of a key 47 and is provided on one side thereof with a grooved collar 48. The forked end 45 of the arm 44 engages the groove of the collar 48 to provide means for sliding the gear 46 relatively to the shaft 23 when the lever 40 is swung relatively to the bearings 32. A gear 49, as best seen in Figure 5, is keyed to the shaft 25 and is disposed to be enmeshed with the gear 46 when the lever 40 is in the position, as seen in Figure 4.

It will thus be seen that the parts 40 to 49, inclusive, provide clutch means for connecting the shaft 23 to or for disconnecting it from the shaft 27.

From the foregoing it will be obvious that the shaft 27 can be turned in a clockwise direction, as indicated by the arrow 35, for turning the shaft 18 in a clockwise direction, as seen in Figure 3, to wind the spring 20. The shaft 27 will be held, as previously explained, from turning in a counterclockwise direction to thereby prevent the shaft 18 from being turned in a counterclockwise direction to unwind the spring 20 from its inner end. As the spring 20 is thus anchored against being unwound from its inner end, the force exerted thereby will cause it to unwind from its outer end thereby turning the drum 19 and the crown gear 21 in a clockwise direction, as seen in Figures 3 and 5. The shaft 23 through the connection of the pinion 25 with the crown gear 21 will be turned thereby in a counterclockwise direction, as indicated by the arrow 50, in Figure 5, and at a substantially greater speed than the speed of rotation of the crown gear 21 due to the relative sizes of the crown gear and the pinion 25. The driving shaft 23 may be employed for any suitable purpose to transmit power as for example through a belt drive, not shown, and may be provided with a belt pulley 51 for this purpose. However, it is to be understood, that the invention may be utilized for any suitable purpose requiring power which can be exerted by a rotating shaft. The clutch means, previously described, is usually in an inoperative position with the lever 40 swung to the left of its position, as seen in Figure 4, for moving the gear 46 to the right and out of engagement with the gear 49. Should the power exerted by the spring 20 be more than is required for the machine to be driven by the shaft 23, the lever 40 can be returned to its position, as seen in Figure 4, to cause the gear 46 to mesh with the gear 49 so that the shaft 23, being turned in a counterclockwise direction will turn the shaft 27 in the opposite or a clockwise direction to thereby

partially rewind the spring 20 so that a portion of the energy exerted by the spring 20 will be exerted for partially rewinding it to thus provide a brake on the spring motor which will utilize at least a portion of the energy which would otherwise be wasted. Obviously, any suitable means such as a crank, not shown, may be employed for turning the shaft 27 for rewinding the spring 20.

Various modifications and changes are contemplated and may obviously be resorted to as only a preferred embodiment of the invention has been disclosed.

I claim as my invention:

1. A spring motor comprising a housing, a perpendicular shaft journaled in the lower portion of said housing, a spring drum through which said perpendicular shaft extends and in which it is loosely disposed, a spiral spring disposed in said spring drum and having its outer end secured to the periphery of the drum and its inner end secured to the perpendicular shaft, a beveled crown gear keyed to said periphery and extending therearound and disposed in said housing, a horizontally disposed shaft extending through said housing, above the crown gear, and journaled therein, and a beveled pinion keyed to said horizontal shaft and enmeshed with the crown gear for rotating the horizontal shaft when the crown gear is turned by the unwinding of the spiral spring.

2. A device as in claim 1, comprising a rewinding shaft extending through said housing and disposed horizontally therein and above the crown gear, a worm keyed to said rewinding shaft, and a worm wheel keyed to the upper end of the perpendicular shaft and enmeshed with said worm for turning the perpendicular shaft relatively to the spring drum to rewind the spring from its inner end, when said rewinding shaft is turned in one direction.

3. A device as in claim 1, comprising a rewinding shaft extending through said housing and disposed horizontally therein and above the crown gear, a worm keyed to said rewinding shaft, a worm wheel keyed to the upper end of the perpendicular shaft and enmeshed with said worm for turning the perpendicular shaft to rewind the spring, when said rewinding shaft is turned in one direction, a gear keyed to the rewinding shaft, a gear slidably keyed to said horizontal shaft, and means for moving said last mentioned gear into and out of mesh with said first mentioned gear whereby when said last mentioned gears are enmeshed the spring will be partially rewound by the power exerted thereby on said horizontal shaft.

4. A spring motor comprising a drum, a shaft journaled therein, a spiral spring disposed in said drum and having its inner end secured to the shaft and its outer end secured to the drum, a crown gear keyed to the drum, a driven shaft, a pinion keyed to said driven shaft and enmeshed with the crown gear, a rewinding shaft, a worm keyed to the rewinding shaft, a worm wheel keyed to said first mentioned shaft and enmeshed with said worm, a gear keyed to the rewinding shaft, a gear slidably keyed to the driven shaft, and means for moving said last mentioned gear into and out of mesh with the gear of the rewinding shaft.

JOHN KALUA KAHOOKANO.
